DRYING-OVEN FOR SHEET MATERIAL

1,288,810.

Specification of Letters Patent. Patented Dec. 24, 1918.

Application filed August 9, 1917. Serial No. 185,324.

To all whom it may concern:

Be it known that I, FERDINAND BIRCHBAUER, a citizen of the United States, residing at Baltimore, in the State of Maryland, have invented new and useful Improvements in Drying-Ovens for Sheet Materials, of which the following is a specification.

This invention relates to improvements in drying apparatus, pertaining more particularly to apparatus adapted for use in the manufacture of printed "tins" or sheets of metal used largely in the manufacture of metallic containers.

15 The sheets or blanks from which metal containers are made are frequently printed in several colors. The application of each color necessitates a separate printing operation, and after each printing the tins or sheets must be dried or baked in order to render the printing effective, to cause the color to adhere, and to prevent smearing, etc., of the sheets. Since the requirements of trade are such as to provide for handling 20 of large quantities of individual tins or sheets, and each must be subjected to the various operations, the handling of the sheets or tins becomes a matter of material importance.

30 Obviously, the time required in completing the printing operations is dependent to a great extent on the length of time required in drying the sheets, since each printing operation is of short duration. Hence 35 the handling of the sheets in locating them in the drier, the length of time required in the drying apparatus, and the handling of the sheets after the drying is completed becomes of material importance. And during 40 the drying operation, the particular manner in which the sheets are dried becomes of importance in order that the amount of damaged sheets or tins be reduced as far as possible. Various ways of meeting the conditions present in the treatment of such sheets 45 or tins have been employed, and it is the general practice to employ a conveyer, preferably of the endless type and which carries a plurality of supports which will enable 50 each sheet to be supported individually during its travel through the drying apparatus.

One type of structures of the endless belt type carries the sheet through one of the flights of the conveyer, the sheet being removed at the end of such flight. Since the

time required in drying the sheet is considerable, this type necessitates the use of a flight of considerable length, ranging up to one hundred feet and over, the conveyer moving at a slow speed through the drying oven. In this type, the other flight of the chain performs no work in the drying operation, the result being that the conveyer operates at but substantially fifty per cent. (50%) of its capacity. The disadvantage 60 of this arrangement will be apparent in considering the cost of heating the drying apparatus where approximately one-half of the conveyer is performing no work.

Attempts to solve these difficulties have 70 led to the employment of another type, in which the sheet is caused to travel practically throughout the length of both flights, thus materially shortening the length of the conveyer and the size of the drying apparatus, reducing the cost of heating the oven and making both flights of the conveyer active. While this advantage resulted by the change, another serious disadvantage arose by reason of the fact that while the sheet, 75 on the upper conveyer flight, could rest with an edge of the sheet on the conveyer itself, the sheet, in rounding from one flight to the other, first placed the sheet on the tray-like support which necessarily extended the full 80 width of the sheet, the sheet then shifting away from the conveyer on to suitable supports carried by the ends of the trays. These sheet movements tend to bring the printed face into contact with the tray or 85 support at one or more points in the travel of the sheet on the conveyer. This contact of sheet and support during sheet movements tends to mark or mar the printing, and this effect is increased by reason of the 90 very slow speed of the conveyer which, while substantially continuous, tends to cause a more or less jerky movement of the conveyer and hence tends to provide sheet shifting movements.

100 The present invention is designed to overcome these and other difficulties by the use of a structure of the endless conveyer type and by means of which the efficiency of the drying apparatus is materially increased. In 105 addition, the apparatus is of a type which is simple and efficient in operation, durable in construction, and which can be installed and operated at a comparatively low cost.

110 To these and other ends, the nature of

which will be readily understood as the invention is hereinafter disclosed, said invention consists in the improved construction and combination of parts hereinafter fully 5 described, illustrated in the accompanying drawings, and more particularly pointed out in the appended claims.

In the accompanying drawings, in which similar reference characters indicate similar 10 parts in each of the views:

Fig. 1 is a view in diagrammatic elevation showing the drying apparatus embodying features of the present invention.

Fig. 2 is a vertical longitudinal sectional 15 view of parts shown in Fig. 1, the parts being shown on an enlarged scale.

Fig. 3 is a sectional view taken on line 3-3 of Fig. 2.

Fig. 4 is a sectional view taken on line 20 4-4 of Fig. 5.

Fig. 5 is a view in side elevation of one end of the drying apparatus, the side walls being omitted to show underlying parts.

Fig. 6 is a detail view showing one form 25 of support which may be employed, portions of conveyer elements being shown in dotted lines.

Fig. 7 is a detail sectional view showing 30 one way in which the trays or supports may be secured to the conveyer.

Fig. 8 is a detail view showing the manner in which an intermediate portion of the tray is supported.

Fig. 9 is a horizontal section, somewhat 35 diagrammatic, of one end of the drier.

Fig. 10 is a detail perspective view.

In the present invention, the apparatus is of the type in which the entire drying operation is provided during travel of the sheet 40 through one flight of the conveyer, the sheet being introduced at one end of the flight and removed at the opposite end. This arrangement however is provided in connection with both flights of the conveyer, each flight 45 thus becoming active in the drying operations, sheets being fed to the apparatus at each end and removed at the opposite end, the inclosing frame of the drier being arranged to permit of such feeding and removal operations. By this arrangement, the 50 heating cost factor is materially reduced, and, in addition, the arrangement permits of the use of ventilating structures by means of which an important advantage accrues 55 with respect to the drying of the individual sheet, viz: the reduction or elimination of the possibility of blistering the sheet. This result is obtained by gradually moving the sheet into a zone of maximum temperature— 60 thus gradually setting the color—the sheet, after passing such zone, moving into gradually decreasing temperatures to the point of removal, thus providing a better finish to the sheet. Since each flight is utilized, 65 the zone of maximum temperature is located

approximately midway of the length of the drying apparatus, the temperatures at the opposite ends being reduced, thus not only providing for this result, but reducing to some extent the necessity for operators 70 working under conditions of extreme temperatures.

In the drawings I have shown, somewhat diagrammatically, one embodiment employing the general principles of the invention. 75 Obviously, these principles may be employed in connection with other forms of structures, and it is to be understood that such changes and modifications as may be found desirable or essential, are considered 80 as falling within the general spirit and scope of the invention, in so far as the same are permitted by the scope of the appended claims when broadly construed.

As shown in Figs. 1 and 2, I preferably 85 employ an elongated casing or housing 10 of sufficient length to receive the endless carrier, the carrier being shown as a conveyer extending around shafts 11 and 12 at opposite ends of the housing. As heretofore 90 pointed out, the sheets or tins are delivered to the carrier at one end of a flight and removed at the opposite end. In the embodiment shown in the drawings the shafts are movable clockwise, and hence the sheets 95 for the upper flight are introduced at the left hand end of Fig. 1, those for the lower flight being introduced at the right hand end of said figure.

To permit of the removal of the sheets, 100 I preferably omit portions of the side walls of the casing or housing at the end of the flight. For instance, in Fig. 1, the sheets from the upper flight are removed at one of the spaces indicated at 13 located in 105 the upper half of the casing, while the sheets from the lower flight are removable through the spaces 14 located in the lower half of the side of the casing. I preferably locate a hood 15 over these spaces, suitable 110 ventilating pipes 16 leading from these hoods, this arrangement tending to permit the heated air which escapes through the open spaces 14 to pass out through pipes 16. The removal of sheets may be had 115 at once side or on both sides of the casing or housing, as may be found desirable, or the particular side may be left optional by the use of removable closures which can be applied to the spaces through which removal is not desired.

As will be seen from Fig. 1, removal openings 14 are arranged only with respect to the particular flight from which the sheets are being removed, thus retaining the oven 125 structure for the adjacent portion of the opposite flight closed, this latter portion being that into which the sheets to be dried are introduced. As it is desired that the portion of the oven to receive such sheets 130

to be of an approximately constant temperature, I provide a horizontal partition 17 at each end—this arrangement being shown in Fig. 2—thus isolating the receiving end 5 of the flight from any effects which might be produced by the presence of the discharge openings of the adjacent flight. As a result, the temperature control can be carried to a point in proximity to the entrance end of each flight and utilizing the 10 length of the heating structure to the maximum. As a result the opposite ends of the housing or casing are practically divided into upper and lower chamber portions, the partitions being located between the opposite flights of the carrier. While the partitions do not extend to the ends of the casing—thus permitting free movement of the carrier in passing from one flight to the 15 other—this does not materially affect the operation described, since the communication between the chambers at the ends is at the point where the sheets are introduced and are being positioned, at which time it is 20 less desirable to subject the sheet to the maximum temperatures.

As shown in Figs. 2 and 3, the interior of the housing or casing is practically divided into upper and lower chambers *a* and *b*, by 25 a horizontal partition 17 formed in suitable manner, this partition being located between the opposite flights of the carrier and being of less length than the length of the housing so that the chambers are in open communication 30 at the ends of the housing. This arrangement practically produces two semi-independent drying chambers, this being especially true at intermediate points in the length of the housing, which points carry 35 the maximum drying temperatures.

Any suitable means may be employed for 40 heating these chambers, a simple arrangement being by the use of a plurality of perforated pipes 18 located within the lower chamber adjacent its bottom and co-operating 45 with suitable members indicated generally at 19, to produce a burner of the Bunsen type, thus heating this chamber, it being understood that any desirable number 50 of structures may be employed and at properly spaced points. Similarly the upper chamber may be heated by pipes located in the partition 17 and which are adapted to be operative at the bottom of the upper 55 chamber, these pipes also forming burners. Obviously, other ways of heating may be employed, those shown being simply illustrative.

As shown more particularly in Fig. 2, I 60 preferably locate ventilating pipes 20 adjacent the ends of the casing, these pipes extending from the top of the casing, a suitable baffle 21 being located below the entrance to pipes 20 in order that the draft 65 through pipes 20 will be effective in ventilation.

ing more or less indirectly, it being necessary for the heat to escape through a somewhat tortuous path.

As will be understood, openings 13 and 14 are more or less effective in the ventilating 70 action, any variation in the number of spaces open—the length of the entire opening—tending to vary the temperatures in an obvious manner.

The carrier, indicated generally at 22, is 75 preferably a fabricated structure made up essentially of a pair of chains 23 composed of links 23^a, chains 23 being spaced apart and adapted to be mounted on sprocket wheels 24 mounted on shafts 11 and 12, intermediate portions of the upper flights of chains 23 being supported on members 25 carried by partition 17, thus preventing sagging of the chains in the upper flight, the lower flight of these chains being supported 85 on bars carried by brackets 26 depending from partition 17, thus preventing sagging of the lower flight of the chains. The chains are driven by connecting one of the shafts, for instance shaft 11, to a source of power, 90 indicated in Figs. 4 and 5, as a drive shaft 27, driven from a suitable point, said shaft carrying a worm 28 adapted to cooperate with a worm gear 29 on shaft 11, thus providing a drive means which will cause a 95 relatively slow movement of the chains through chambers *a* and *b*.

Each link 23^a is preferably provided with a stud 30, projecting inwardly, each stud having a lateral opening 30^a adapted to receive one of the arms 31^a of a tray 31, the arm being secured in position by suitable means such as a set screw 30^b (Fig. 7). It is to be understood, of course, that chains 23 are so positioned that the stud of a link of one chain is directly opposite the stud of the corresponding link of the other chain, the two studs thus being substantially in alignment. This positioning may be provided by the mounting of sprockets 24.

The trays 31 are formed of heavy wire or 100 steel bars of small cross-section, these wires or bars being bent to produce the arms 31^a at the ends of the bars or wires, these arms projecting outwardly. The outer ends of the arms lead to hook shaped portions 31^b which project rearwardly with respect to the direction of travel of the carrier, the hook shaped portions 31^b being joined by a more or less V-shaped connecting portion 31^c which may 105 extend inwardly a suitable distance, and which preferably, although not necessarily, extends inward a distance sufficient to permit its connection with a link 32^a forming one of the members of a fabricated chain 110 32 arranged midway between chains 23.

Where the chain structure 32 is employed, 115 links 32^a will obviously correspond in length to links 23^a, so that travel of the intermediate portion of the tray will correspond to the 120

travel of arms 31^a. Chain 32 is mounted on sprockets 33, and may have its intermediate portion supported similarly to chains 23, although this is not absolutely essential, 5 since each tray, being supported directly at its ends will tend to support chain 32 against sagging. Sprocket wheels 33 may be loose or fast on the shafts as may be desired.

As shown in Fig. 2, the trays are prefer- 10 ably inclined rearwardly toward their outer ends with respect to the direction of travel.

As shown more particularly in Fig. 2 the sheets or tins are introduced as the trays are rounding the connecting portions of the 15 flights at which time the outer ends of the trays are spread apart, the spread being of sufficient distance to permit of the ready introduction of a sheet or tin between successive trays, even though successive trays, 20 in the straight flights, have their outer ends in proximity to each other.

The sheets or tins may be introduced in any suitable manner, either manually or by transfer mechanism which may be arranged 25 so as to provide for a complete automatic feed. In the drawings I have shown a conveyer 34 at each end of the oven, these conveyers being adapted to receive the sheets from presses 35, the showing of these elements being diagrammatic. As will be understood, the sheets are positioned on the conveyer with the printed side uppermost, and are inserted into the space between trays 30 in this manner. The sheets introduced at the left end of Fig. 2 rest upon that side of the tray opposite the side carrying hook members 31^b, unprinted faces of the sheets facing the supporting tray, the printed faces facing the preceding tray. The sheets or 35 tins delivered at the right end of the oven are also introduced between successive trays with the printed faces uppermost. At this end, however, the introduced sheet is supported on that side of the tray from which the hooks 31^b project, so that as the chain 40 carries the introduced sheet forward, the sheet is supported against dropping by the hooks of the tray, with the unprinted side facing the remainder of the tray. Since the 45 trays are inclined rearwardly, it will be understood that there is practically no liability of the positioned sheet shifting its position after rounding the connecting portion of the flights, and during this period 50 the sheets are supported by the trays with the unprinted face of the sheet as the only portion in contact with the tray. Hence the relative positions of the sheets are maintained throughout their travel through the 55 oven, the sheets, as heretofore pointed out, being removed at openings 13 or 14 before beginning to round the ends of the flights, so that practically no accidental shifting of the sheets will be had while in the oven.

60 In this latter connection, this effect is in-

creased—especially in the upper flight—by the form of links 32^a, shown in Fig. 8, these links tending to shift the lower edge of the introduced sheet away from the tray and thus increase the angularity of the sheet on 70 the tray.

Where the sheet carries a plurality of colors, successive printing may be provided on different presses, so that the sheets from one press may, after passing through the 75 drier, be delivered adjacent to the point where the succeeding color is to be provided. However, this is not obligatory since the removed sheets at either end are limited to those of a single press, so that while sheets 80 of two presses are being dried concurrently, there is no mixing of sheets, so that the successive colors can be applied on the same press, which may be advantageous in insuring registration by completing the printing 85 on a single press.

By rendering both flights of the carrier active and completing the drying action on each flight, the heat cost factor is materially reduced, and the capacity of the drier is 90 greatly increased, the close arrangement of the trays permitting a large number of sheets to be undergoing treatment concurrently with each sheet receiving its proper treatment. While this increases the dead 95 load weight, provision is made for supporting this weight so as not to affect the operation of the carrier.

While I have herein shown and described a preferred form of apparatus, it will be 100 readily understood that changes or modifications therein may be required or desired to meet the exigencies of use, and I desire to be understood as reserving the right to make any and all such changes or modifications as 105 may be found necessary or desirable, in so far as the same may fall within the spirit and scope of the invention as expressed in the accompanying claims when broadly construed.

110 In view of the fact that lengths of sheets may vary in different types of work and the further fact that feeding to the drier may not be uniform, I prefer to employ means tending to guide the sheet to predetermined positions to insure substantially uniform sheet positioning on the traveling support. This means may be of any preferred arrangement, a simple mechanism for the purpose being the use of a pair of bars or members 40 having outwardly flared or inclined forward ends 40^a, as in Fig. 9, these bars or members being adjustably supported so as to permit increase or decrease in the distance between the bars or members. These structures are 115 120 125 preferably located at both feeding ends of the drier.

I also prefer to employ a sheet supporting guide or member in connection with the feeding means for the lower flight, the 130

guide or member being adapted to prevent the rear end of the sheet from being freed from support before it reaches a point on the sheet-supporting member of the carrier sufficiently beyond the hook-shaped ends of the carrier member to ensue this edge of the sheet entering the hook. This member is shown in detail in Fig. 10 as in the form of an arm or finger 41 secured to the oven frame and extending to or into the facial plane of the roll 34^a of conveyer 34. The finger configuration acts to augment the sheet advancing movement provided by the sheet delivering mechanism. Obviously where roll 34^a extends into the path of travel of the carrier members sufficiently to cause sheet delivery at the proper point, member 41 may be omitted.

Having thus described my invention, what I claim as new, is:

1. A drier for printed sheets comprising an oven structure having an inlet opening at each end through which printed sheets may be fed, and an endless carrier having approximately parallel flights extending in the direction of length of the oven with the ends of the flights positioned adjacent said inlet openings, said carrier having a plurality of closely-arranged sheet-supporting members active in both flights, said oven structure having a length to permit complete drying treatment of the sheet during its travel in either flight and having an opening at each end positioned to permit access to the carrier flights for removal of sheets after completion of the drying treatment and in advance of movement of the supporting member to a position to receive the succeeding sheet.

2. A drier for printed sheets comprising an oven structure having an inlet opening at each end through which printed sheets may be fed and also having a partition extending in the direction of length of the oven and dividing the latter into upper and lower chambers, said chambers being in open communication at the ends of the oven structure, and an endless carrier having approximately parallel flights extending in the direction of length of the oven, said flights being on opposite sides of the partition to locate a flight in each of said chambers, the ends of the flights being positioned adjacent said inlet openings and within the portions of open communication between the chambers, said carrier having a plurality of closely-arranged sheet-supporting members active in both flights, said oven structure having a length to permit complete drying treatment of the sheet during its travel through either chamber, and having an opening at each end positioned to permit access to the carrier flights for removal of sheets after completion of the drying treatment and in advance of movement of the supporting member to a position to receive the succeeding sheet.

3. A drier for printed sheets comprising an oven structure having an inlet opening at each end through which printed sheets may be fed and also having a partition extending in the direction of length of the oven 70 and dividing the latter into upper and lower chambers, said chambers being in open communication at the ends of the oven structure, an endless carrier having approximately parallel flights extending in the direction of 75 length of the oven, said flights being on opposite sides of the partition to locate a flight in each of said chambers, the ends of the flights being positioned adjacent said inlet openings and within the portions of open 80 communication between the chambers, said carrier having a plurality of closely-arranged sheet-supporting members active in both flights, said oven structure having a length to permit complete drying treatment of the 85 sheet during its travel through either chamber, and having an opening at each end positioned to permit access to the carrier flights for removal of sheets after completion of the 90 drying treatment and in advance of movement of the supporting member to a position to receive the succeeding sheet, and means for heating said chambers.

4. A drier for printed sheets comprising an oven structure having an inlet opening 95 at each end through which printed sheets may be fed, an endless carrier having approximately parallel flights extending in the direction of length of the oven with the ends of the flights positioned adjacent said inlet 100 openings, said carrier having means for supporting a plurality of closely-arranged but spaced-apart sheets in both flights, said oven structure having a length to permit complete drying treatment of the sheet during 105 its travel in either flight and having an opening at each end positioned to permit access to the carrier flights for removal of sheets after completion of the 110 drying treatment and in advance of movement of the supporting member to a position to receive the succeeding sheet, said oven structure being divided in proximity to such removal openings to permit positioned sheet introduction into a closed portion of the oven. 115

5. A drier for printed sheets comprising an oven structure having an inlet opening at each end through which printed sheets may be fed, an endless carrier having approximately parallel flights extending in the 120 direction of length of the oven with the ends of the flights positioned adjacent said inlet openings, said carrier having means for supporting a plurality of closely-arranged but spaced-apart sheets in both 125 flights, said oven structure having a length to permit complete drying treatment of the sheet during its travel in either flight and having an opening at each end positioned to permit access to the carrier flights for re- 130

- removal of sheets after completion of the drying treatment and in advance of movement of the supporting member to a position to receive the succeeding sheet, and means for heating and ventilating said oven, said oven structure being divided in proximity to such removal openings to permit positioned sheet introduction into a closed portion of the oven.
10. A drier for printed sheets comprising an oven structure having an inlet opening at each end through which printed sheets may be fed, an endless carrier having approximately parallel flights extending in the direction of length of the oven with the ends of the flights positioned adjacent said inlet openings, said carrier having means for supporting a plurality of closely-arranged but spaced-apart sheets in both flights, said oven structure having a length to permit complete drying treatment of the sheet during its travel in either flight and having an opening at each end positioned to permit access to the carrier flights for removal of sheets after completion of the drying treatment and in advance of movement of the supporting member to a position to receive the succeeding sheet, and means for heating and ventilating said oven, said latter means including controllable regulation of the length of the sheet-removing opening, said oven structure being divided in proximity to such removal openings to permit positioned sheet introduction into a closed portion of the oven.
7. A drier for printed sheets comprising an oven structure having an inlet opening at each end through which printed sheets may be fed, an endless carrier having approximately parallel flights extending in the direction of length of the oven with the ends of the flights positioned adjacent said inlet openings, a partition extending in the direction of length of the oven and positioned between said carrier flights, and means for supporting the carrier to provide flight movements substantially parallel to the direction of length of the partition, said carrier having a plurality of closely-arranged sheet-supporting members active in both flights.
8. A drier for printed sheets comprising an oven structure having an inlet opening at each end through which printed sheets may be fed, an endless carrier having approximately parallel flights extending in the direction of length of the oven with the ends of the flights positioned adjacent said inlet openings, a partition extending in the direction of length of the oven and positioned between said carrier flights, and means for supporting the carrier to provide flight movements substantially parallel to the direction of length of the partition, said carrier having a plurality of closely-arranged sheet-supporting members active in both flights, said carrier supporting means including a pair of members supported by the partition and on which the carrier is adapted to travel.
9. A drier for printed sheets comprising an oven structure having an inlet opening at each end through which printed sheets may be fed, an endless carrier having approximately parallel flights extending in the direction of length of the oven with the ends of the flights positioned adjacent said inlet openings, a partition extending in the direction of length of the oven and positioned between said carrier flights, and means for supporting the carrier to provide flight movements substantially parallel to the direction of length of the partition, said carrier having a plurality of closely-arranged sheet-supporting members active in both flights, said supporting means including elements supported by the partition within the lower chamber and adapted to support the carrier against sagging during travel through said chamber.
10. A drier for printed sheets comprising an oven structure having an inlet at each end through which printed sheets may be fed, an endless carrier having approximately parallel flights extending in the direction of length of the oven with the ends of the flights positioned adjacent said inlet openings, said carrier having a plurality of closely-arranged sheet-supporting members active in both flights, said oven structure having a length to permit complete drying treatment of the sheet during its travel in either flight and having an opening at each end positioned to permit access to the carrier flights for removal of sheets after completion of the drying treatment, the lengths of said openings being variable to control oven temperatures, said oven structure being divided in proximity to such removal openings to permit positioned sheet introduction into a closed portion of the oven.
11. A drier for printed sheets comprising an oven structure having an inlet at each end through which printed sheets may be fed, an endless carrier having approximately parallel flights extending in the direction of length of the oven with the ends of the flights positioned adjacent said inlet openings, said carrier having a plurality of closely-arranged sheet-supporting members active in both flights, said oven structure having a length to permit complete drying treatment of the sheet during its travel in either flight and having an opening at each end positioned to permit access to the carrier flights for removal of sheets after completion of the drying treatment, the lengths of said openings being variable to control oven temperatures, hood structures external of the oven and extending over said sheet.

removing openings, and ventilating devices carried by said hood structures.

12. A drier for printed sheets comprising an oven structure having an inlet opening 5 at one end through which printed sheets may be fed and an outlet opening at its opposite end through which the sheets may be removed, said oven structure having a length to permit complete drying treatment 10 of the sheet during its travel from the inlet to the outlet opening, a traveling carrier in said oven for supporting successive sheets to travel from the inlet to the discharge opening, and means for controlling the temperatures 15 of the oven to locate the zone of maximum temperature intermediate said openings and to provide decreasing temperatures from said zone toward each of said openings, whereby a traveling sheet will first be 20 subjected to increasing temperatures and then to decreasing temperatures.

13. A drier for printed sheets comprising an oven structure having an inlet opening at one end through which printed sheets 25 may be fed and an outlet opening at its opposite end through which the sheets may be removed, said oven structure having a length to permit complete drying treatment of the sheet during its travel from the inlet to the 30 outlet opening, a traveling carrier in said oven for supporting successive sheets to travel from the inlet to the discharge opening, and means for controlling the temperatures of the oven to locate the zone of maximum 35 temperature intermediate said openings and to provide decreasing temperatures from said zone toward each of said openings, whereby a traveling sheet will first be 40 subjected to increasing temperatures and then to decreasing temperatures, said controlling means including regulation of the length of the sheet-removal opening.

14. A drier for printed sheets comprising an oven structure having an inlet opening 45 at one end through which printed sheets may be fed and an outlet opening at its opposite end through which the sheets may be removed, said oven structure having a length to permit complete drying treatment 50 of the sheet during its travel from the inlet to the outlet opening, a traveling carrier in said oven for supporting successive sheets to travel from the inlet to the discharge opening, and means for controlling the temperatures 55 of the oven to locate the zone of maximum temperature intermediate said openings and to provide decreasing temperatures from said zone toward each of said openings, whereby a traveling sheet will 60 first be subjected to increasing temperatures and then to decreasing temperatures, said controlling means including ventilating devices active at the ends of the oven, and means for regulating the length of the sheet- 65 removal opening.

15. In a drier for printed sheets, an oven structure having an inlet opening at each end through which printed sheets may be fed, and an endless carrier having approximately parallel flights extending in the direction of length of the oven with the ends of the flights positioned adjacent said inlet openings, said carrier including a pair of chains formed of links, and trays carried by corresponding links of said chains for supporting sheets individually, each tray having rearwardly projecting hooks, said oven structure having a length to permit complete drying treatment of a sheet during its travel in either flight and an opening 80 at each end positioned to permit access to the carrier flights for removal of sheets, sheets in one flight contacting with the chains and sheets in the other flight being supported by the hooks. 85

16. In a drier for printed sheets, an oven structure having an inlet opening at each end through which printed sheets may be fed, and an endless carrier having approximately parallel flights extending in the direction of length of the oven with the ends of the flights positioned adjacent said inlet openings, said oven having a length to permit complete drying treatment of the sheet during its travel in either flight and having an opening at each end positioned to 90 permit access to the carrier flights for removal of sheets after completion of the drying treatment, said carrier including chains for supporting a plurality of closely-arranged sheet-supporting trays, each tray having rearwardly projecting hook portions and an intermediate substantially V-shaped connecting portion, and an intermediate chain to which the V-shaped portion is connected. 95

17. In a drier for printed sheets, an oven structure having an inlet opening at one end thereof through which printed sheets may be fed, an endless carrier having approximately parallel flights extending in the direction of length of the oven, said carrier including chains carrying a plurality of closely-arranged sheet-supporting trays, each tray having rearwardly-projecting hook portions and an intermediate substantially V-shaped connecting portion, and an endless carrier to which the V-shaped portion of each tray is connected. 110

18. A drier for printed sheets comprising an oven structure having an inlet opening at each end through which printed sheets may be fed, an endless carrier having approximately parallel flights extending in the direction of length of the oven with the ends of the flights positioned adjacent said inlet openings, said carrier having a plurality of closely-arranged sheet-supporting members active in both flights, said oven structure having a length to permit com- 125 130

plete drying treatment of the sheet during its travel in either flight and having an opening at each end positioned to permit access to the carrier flights for removal of 5 sheets after completion of the drying treatment and in advance of movement of the supporting member to a position to receive the succeeding sheet, and means coöperating with sheet ends for guiding the sheets 10 to substantially predetermined positions on the sheet-supporting members.

19. A drier for printed sheets comprising an oven structure having an inlet opening at each end through which printed sheets 15 may be fed, an endless carrier having approximately parallel flights extending in the direction of length of the oven with the ends of the flights positioned adjacent said inlet openings, said carrier having a plurality of closely-arranged sheet-supporting members active in both flights, said oven structure having a length to permit complete drying treatment of the sheet during its travel in either flight and having an 20 opening at each end positioned to permit access to the carrier flights for removal of sheets after completion of the drying treatment and in advance of movement of the 25

supporting member to a position to receive the succeeding sheet, and means coöperating with sheet ends for guiding the sheets to substantially predetermined positions on the sheet-supporting members, said means being adjustably supported to permit adjustment relative to the travel path of the 30 flights.

20. In a drier for printed sheets wherein sheets may be delivered into either flight of a horizontally-disposed endless carrier having a plurality of closely-arranged sheet- 40 supporting members active in both flights, and means for controlling the delivery of sheets to predetermined positions on said members, said means including a sheet-delivery carrier mechanism, and a stationary 45 member or finger coöperating with the delivery mechanism to augment the sheet-advancing movement of the delivery mechanism.

In testimony whereof I have hereunto set 50 my hand in presence of two subscribing witnesses.

FERDINAND BIRCHBAUER.
